COMPOSITE WOOD AND METAL SKI

Filed Dec. 4, 1943

UNITED STATES PATENT OFFICE

2,434,851

COMPOSITE WOOD AND METAL SKI

Christian K. Hoerle, Torrington, Conn.

Application December 4, 1943, Serial No. 512,865

9 Claims. (Cl. 280—11.13)

1

This invention relates to metallic skis and more particularly to a ski having a foot-supporting filler block of wood embraced by a snow-engaging U-shaped base of corrosion-resistant metal.

One object of the present invention is to provide a composite wood and metal ski of the above nature, in which the filler block is held upon the base by a pair of Z-shaped metal anchor members welded or soldered to said base.

A further object is to provide a ski of the above nature in which the front and rear ends of the filler block are protected by inverted U-shaped cover members of metal telescoped within the upstanding sides of the U-shaped base.

A further object is to provide a ski of the above nature in which provision is made of a metal reinforcing point at the upturned forward part of the base which is secured rigidly in position by welding or soldering.

A further object is to provide a composite wood and metal ski of the above nature, which will be simple in construction, inexpensive to manufacture, easy to assemble, compact, ornamental in appearance, and very efficient and durable in use.

With these and other objects in view, there has been illustrated on the accompanying drawings one form in which the invention may conveniently be embodied in practice.

In the drawing,

Fig. 1 represents a side view in elevation of a ski embodying the present invention.

Fig. 2 is a top plan view of the same.

Fig. 3 is a longitudinal sectional view of the rear part of the ski, taken along the line 3—3 of Fig. 2, looking in the direction of the arrows.

Fig. 4 is a longitudinal sectional view of the forward part of the ski, taken along the line 4—4 of Fig. 2.

Fig. 5 is a perspective view of the foot-supporting filler block.

Fig. 6 is a bottom plan view of the ski.

Fig. 7 is a perspective longitudinal sectional view of a portion of the rear part of the ski showing the interlocking engagement of the rear anchor member with the rear end of the filler block.

Fig. 8 is a transverse sectional view of the rear part of the ski, taken along the line 8—8 of Fig. 2.

Fig. 9 is a transverse sectional view of an intermediate part of the ski, taken along the line 9—9 of Fig. 2.

Fig. 10 is a perspective view of one of the anchor members.

Fig. 11 is a perspective longitudinal sectional

2

view of the upturned curved forward portion of the ski.

Referring now to the drawing, in which like reference numerals denote corresponding parts throughout the several views, the numeral 10 indicates the flat base of the ski, which is U-shaped in cross section and constructed of corrosion-resistant metal. The base 10 has a longitudinal groove 11 in its bottom surface and is provided with a pair of upturned sides 12 and 13 connected with a pair of downturned inner wings 14 and 15 located within said upturned sides 12 and 13, as clearly shown in Figs. 8 and 9.

Provision is also made of a foot-supporting filler block 16 seated in said U-shaped base 10 and embraced by said wings 14 and 15. The filler block 16 has a raised foot rest section 17 located slightly to the rear of the mid-point of the ski base 10.

10 The filler block 16 is adapted to be held securely upon the base 10 by means of a pair of rear and front Z-shaped anchor members 18, 19, the upper flanges of which are adapted to overlap and engage the flat ends of the block 16 (as clearly shown in Figs. 2, 3, 4, and 7).

15 The rear portion of the filler block 16 and the rear anchor member 18 are adapted to be embraced by a U-shaped cover member 20 having a downturned rear edge 21 fitted inside an upturned rear edge 22 of the base 10 of the ski.

20 The rear cover member 20 is provided with depending sides 23, 24 which (as shown in Fig. 8) are adapted to fit tightly within and be secured as by welding or soldering to the inner downturned wings 14, 15 of the metal ski base 10.

25 At the front of the ski, provision is made of a curved upturned U-shaped cover member 25 which is adapted to embrace the front part of the filler block 16 and the Z-shaped anchor member 19. The cover member 25 is secured as by welding or soldering, to the downturned wings 14, 15 of the sides 12, 13 of the ski base 10. The cover member 25 is also welded to a curved U-shaped reinforcing point 26 of thicker metal than the sheet material of the metal base 10.

30 The filler block 16 is adapted to be detachably connected to a foot harness by means of a pair of horizontal headed screws 27, 28 screwed into the opposite sides of the raised section 17 of said filler block 16, the straps of said harness being indicated in dotted lines by the numerals 29, 30, in Fig. 9.

35 For the purpose of reinforcing the headed harness attaching screws 27, 28, provision is made of a narrow U-shaped thin metal bracket 31

lying transversely underneath the foot rest 17 and having a longitudinal groove 32 interfitting with the groove 11 in the bottom of the ski base 10.

Operation

In the manufacture of the composite wood and metal ski of the present invention, the base will preferably be rolled into the shape of a U from a strip of metal by any suitable mechanism, (not shown). The undersurface of the lower flange of the rear Z-shaped anchor member 18 will then be welded to the top surface of the base 10 at the position shown in Fig. 2. The elongated wooden filler block 16 with the reinforcing bracket 31 attached thereto will then be laid within the base 10 in the position shown in Fig. 2, with its rear end inserted under the upper flange of the anchor member 18. The forward anchor member 19 will then be welded or soldered to the base 10 in the position shown. The next step in the assembly of the ski will be to install the telescoping protecting covers 20, 25, as clearly shown in the drawings, which covers may then be welded or soldered to the inner wings of the base 10.

While there has been disclosed in this specification, one form in which the invention may be embodied, it is to be understood that this form is shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new and for which it is desired to secure Letters Patent is:

1. In a ski, a substantially flat elongated metal base having upturned sides, a top filler block seated in said base between the sides thereof, a pair of Z-shaped filler block holding anchor members having their bases secured to the base of the ski at the front and rear ends of said filler block, and a pair of inverted U-shaped metallic protective covers for the front and rear portions of said filler block, said covers being secured to the sides of said ski base.

2. In a ski, as defined in claim 1, a U-shaped metal protective tip of thicker metal than the remainder of the base of the ski secured to the front of said base and to the front protective cover.

3. In a composite wood and metal ski, an elongated metal base having upturned sides, a wooden filler block seated within said base and fitted within the sides thereof, a pair of inverted U-shaped cover members for embracing the front and rear portions of said filler block, said cover members having downturned sides telescoping with the upturned sides of said base, and means for securing the sides of said cover members to the sides of said base.

4. A ski as defined in claim 3, in which the upturned sides of said base are provided with downturned inner wings, and the downturned sections of said cover members are fitted within and secured to said wings.

5. In a ski, an elongated metal base having upturned sides, a filler block anchored in said base

and fitted within the sides thereof, said filler block having a raised foot rest, a pair of horizontal harness-attaching headed members projecting from the opposite sides of said raised foot rest above the edges of the upturned sides of said metal base, and a U-shaped metal reinforcing bracket having its side members embracing said headed members and located between said base and said filler block.

6. In a ski, a substantially flat elongated metal base having upturned sides, a top filler block seated in said base between the sides thereof, and a pair of Z-shaped filler block holding anchor members having their bases secured to the base 15 of the ski at the front and rear ends of said filler block.

7. In a ski, an elongated metal base having upturned sides, a filler block seated within said base and fitted within the sides thereof, means 20 to secure said filler block to said base, a pair of inverted metallic cover members having downturned sections to embrace the front and rear portions of said filler block, said downturned sections being telescoped within the upturned sides of said base, and means to secure the sides of said cover members to the upturned sides of said base.

8. In a ski, an elongated metal base having upturned sides, a filler block seated within said 30 base and fitted within the sides thereof, means to secure said filler block to said base, and a pair of inverted metallic cover members having downturned sections to embrace the front and rear portions of said filler block, said downturned sections 35 being telescoped within the upturned sides of said base, the sides of said cover members being welded to the upturned sides of said base.

9. In a ski, an elongated metal base having upturned sides, a filler block seated within said 40 base and fitted within the sides thereof, means to secure said filler block to said base, a pair of inverted metallic cover members having downturned sections to embrace the front and rear portions of said filler block, said downturned sections 45 being telescoped with respect to the upturned sides of said base, and means to secure the sides of said cover members to the upturned sides of said base.

CHRISTIAN K. HOERLE.
